UNITED STATES PATENT OFFICE.

GEORGE CHALMERS, OF SAN JUAN, CALIFORNIA.

RAILWAY-SWITCH.

SPECIFICATION forming part of Letters Patent No. 319,067, dated June 2, 1885.

Application filed April 14, 1884. (No model.)

To all whom it may concern:

Be it known that I, GEORGE CHALMERS, of San Juan, county of San Benito, and State of California, have invented an Improvement in 5 Railway-Switches; and I hereby declare the following to be a full, clear, and exact description thereof.

My invention relates to a new and useful railway-switch of that class in which levers in 10 the road-bed are operated by suitable devices on the passing locomotive to throw the switch-rails into or out of connection with the main or side track.

My invention consists in a novel arrangement and construction of the levers in the 15 road-bed, and in their connection with the throw or switch rails, in details of construction connected therewith, and in the novel arrangement of devices on the locomotive by 20 which said levers are operated, all of which I shall hereinafter fully describe.

The object of my invention is to provide a simple and effective automatic railway-switch.

Referring to the accompanying drawings, 25 Figure 1 is a plan of the road-bed. Fig. 2 is a perspective view showing the lever F with surrounding parts. Fig. 3 is a perspective view showing the engagement of lever I with the tie-bar of the throw-rails. Fig. 4 is a 30 cross-section on the line x x of Fig. 3, showing the means by which the throw-rails are temporarily locked and the means for releasing them. Fig. 5 is a detail perspective showing the engagement of lever I with the 35 tie-rod c. Fig. 6 is a side elevation of the locomotive and a section on line y y, Fig. 7, showing the casing O in section to reveal the devices contained within it. Fig. 7 is a bottom view of the casing O and locomotive. 40 Fig. 8 is a top view of same. Fig. 9 is a cross-section on line 1 2 of Fig. 6, showing the leg T with its feet t t. Figs. 10, 11, and 12 are views showing the different positions of the 45 feet and the mechanisms for operating said feet.

A is the road-bed. B is the main track, and

C the intervening throw-rails.

D is the right-hand side track, and E is the left-hand side track.

In the road-bed at a suitable distance from 50 the throw-rails is pivoted by one end a long lever, F, having a spear-like shape in super-

ficial area. It lies parallel with the rails, and is bent near its pivoted end in such manner that it lies above and clear of the road-bed. On each side of the lever is a raised guide-bar, 55 G, and between these the lever moves.

H is a T-shaped lever pivoted at the center of its arms in the road-bed under the point of lever F. Its leg portion is bent upward under the body of F, and is secured thereto by 60 means of a stud, f, on lever F passing through it. The movement of lever F turns lever H on its pivot. Pivoted in the road-bed beyond the free ends of the throw-rails is a lever, I, having arms i at right angles. The free end 65 of lever I is connected with a tie-bar, c, between the throw-rails. Rods J connect the arms i of lever I with the arms of lever H, whereby the movement of the latter lever, as heretofore described, transmits motion to lever I with such effect that the rails C are thrown into connection with the main or side tracks. In the road-bed farther on are the 70 parts which operate to throw rails from the opposite direction. These consist of the 75 spear-like lever F', arranged in the main track, the parallel side guide-rails, G', the T-shaped lever H', united with lever F' by a stud, and the rods J', connecting the arms of lever H' with those of lever I. All these parts are arranged and operate similarly to their equivalent or corresponding parts already described. 80

There are some details of construction in connection with the devices described which it will be well to mention at this point. 85

In order to obtain a greater or less leverage in the connection between the levers F F' and the levers H H', the legs of the latter are slotted in order that the studs may be moved therein, and the levers F F' are provided at 90 their bases with a series of holes, a a', whereby they are adapted to slide or move on levers H H' to the required point, and be again pivoted to the road-bed, Fig. 2.

In order to temporarily lock the throw-rails 95 C where adjusted, the tie-bar c is provided on its under side with a rib, c'. This is adapted to drop into sockets b, formed in a box in the road-bed under the tie-bar, and so spaced as to correspond to the movement of the throw-rails, Fig. 4. The rib c' is raised out of the 100 sockets both by reason of their beveled sides

and by the following device: Upon the center of the tie-bar is an upright arm, c^2 , having a wide notch in its top, Figs. 4, 5. To this arm is pivoted a strip, d , having oppositely-extending legs d' , in the ends of which are mounted wheels or rollers d^2 , which travel on a suitable base or track in the road-bed, Fig. 4. The end of lever I passes through the top of strip d , above its pivot-point 6, and extends within the wide notch of arm c^2 . When the lever is moved, its first effect is to throw the top of strip d over to one side, thus throwing its roller d^2 on that side down against the track on which it runs, and by bearing on it raises the tie-rod c and throw-rails C, thus lifting the rib c' out of the socket.

The following power of the lever I is directed against the notched arm c^2 , (which momentarily it did not affect because of its notch being enough wider than the end of the lever I,) and thus moves the throw-rails until the rib c' under the tie-rod comes to and drops into the next socket b. I have also provided for operating the throw-rails by hand.

K is the switch-lever connected by a rod, k, with a cross-bar, k', secured to the lever I.

I shall now describe the mechanism on the locomotive by which the levers F F' are engaged to operate the switch.

L is the locomotive. Under the cab is mounted a rock-shaft, M, to which is connected a lever, N, extending upward within the cab. This lever is adapted to engage with a rack, N', having three notches—to wit, a central one, and one at each end, Fig. 6. From the center of shaft M extends a crank-arm, m. Under the locomotive is bolted a casing or frame, O, having an open top and a closed bottom, through the forward portion of which, at each edge, are made holes o, and similar holes, o', though larger, are made through said bottom near its rear portion. The ends of the casing serve as exterior end walls for these holes, and a solid center to the casing serves as interior end walls. The sides of casing serve as exterior side walls for them, and a vertical partition between the rear holes serves as inner side walls for said rear holes, but the forward holes have no dividing-wall other than the floor of the casing. These holes thus practically become passages for guiding the legs and feet, hereinafter described.

Mounted transversely in the rear top of the casing is a shaft, P, on which are pivoted arms, the arms Q Q' on the right and left hand sides, respectively, viewing them from the cab, Fig. 8. To the forward ends of these arms are pivoted the stems or legs R R', respectively, extending each downwardly through the rear passages, o', their feet r r' being adapted to project through said passages, Figs. 6, 7, 8. These feet are made oval or elliptical in shape, as shown.

Pivoted at 5, between the sides of the casing, more toward the front, is a wide lever, S, to the forward end of which is pivoted a leg, T, terminating in two feet, t, which are

adapted to project through the forward holes or passages, o, Figs. 7, 9.

Extending from the rear of lever S is an upwardly-curved arm, s, having a curved slot made in it, Fig. 6. The arm Q is slotted horizontally (see Figs. 11 and 12) near its middle, and the arm Q' is likewise slotted at its forward end, Figs. 6, 8. Mounted across the top of the casing is a crank-shaft, U. This shaft has three cranks—one near each end and a central one. The end ones, u, are one hundred and eighty degrees apart, and the central one, u', is between them, being ninety degrees from each, Fig. 8. The end cranks pass through the slotted arms Q Q', and the center crank passes through the slotted arm s. A rod, V, joins the central crank with the crank-arm m of the rocking shaft M, Fig. 6.

The operation of these devices is as follows: When the lever N in the cab is pulled back to the rearmost notch of its engaging-rack, the left-hand foot r' is projected through its passage and extends below the casing. The right-hand foot r is withdrawn within its passage to its uppermost limit, and the forward feet, t, are also withdrawn. Move the lever to its central notch. The left-hand foot r' is withdrawn to lie flush with the bottom of the casing, the right-hand foot r is moved down to lie flush with the bottom of the casing, and the forward feet, t, are projected through holes o and extend below the casing. Move the lever N to its forward notch. The left-hand foot r' is withdrawn to its inner limit, the right-hand foot r is projected below the casing, and the forward feet, t, are withdrawn. The relation of these feet to the devices heretofore described in the road-bed and their operation in connection therewith, I will now describe.

The forward feet, t, are made narrow, so as to be able to pass between the edges of the levers F F' and the side guide-bars, G G', and they are separated by such a distance that when so passing they force the said levers into a perfectly-straight position and leave them parallel with the rails. This position of the levers straightens the levers H H' and throws the switch-rails straight, so that they connect with the main track. When these feet are thrown down for such engagement, the rear feet are both withdrawn, as will be seen by reference to the previous description, and they do not therefore interfere. The rear feet are each made wider than the forward feet, and of such width that when either of them passes between the edge of levers F F' and the guide-bar it forces said levers beyond a straight line over to the other side, leaving them in an inclined position and the throw-rails in connection with either side track, according to the side to which the levers are forced; and by reference to the previous description it will be seen that when one of these rear feet is projected for its engagement the other is withdrawn, and when either is projected the forward feet are withdrawn. The oval shape of the feet

and the spear-like shape of the levers permit an easy and accurate engagement. When the locomotive is passing the stretch of road between the two levers, and it is desired to keep the locomotive to the main track, but to leave the switch set for the siding, such feet can be projected to engage with the lever to which the locomotive is approaching as are necessary to leave the switch in such desired position; but in case the locomotive is to go off on one of the side tracks, and it is desired that it should leave the switch set for the main track, then it is obvious that such feet as I have heretofore described will be carried out of relation with the lever and will not engage with it to operate it. The necessity for this result of leaving the switch set for the main track when the locomotive has taken the siding is quite frequent in making up trains, where the locomotive runs onto the siding and has to let the cars follow on the main track. To accomplish this I have the following means: Secured to the sides of the locomotive are downwardly-projecting plates W , the lower ends of which are bolted to the sides of the casing O . A space is left between the plates and the sides of the casing, in which are pivoted curved bars or levers X X' , the downturned ends of which are formed into feet x x' , the foot x being on the right and the foot x' on the left hand side when viewed from the cab. The right-hand bar X has pivoted to it, behind its pivot-point, a link, Y , extending upwardly and pivoted to the lower end of a link, Z , the upper end of which is pivoted to the inner side of the frame of the locomotive, Fig. 6. This link Z is inclined toward the front from its top to bottom. The left-hand bar X' has pivoted to it, behind its pivot-point, a link, Y' , extending upwardly and pivoted to the lower end of a link, Z' , pivoted at its upper end. This link is inclined in a direction opposite to the link Z , Fig. 8. Secured to the crank-arm m of the rocking shaft M are the rods A' A^2 , the former extending to and engaging with a stud, y , projecting inwardly from the top of link Y , and the latter extending to and engaging with a stud, y' , on the link Y' , Fig. 8. On account of the different inclinations of the links Z Z' the effect of the rocking shaft is to raise the foot x while depressing the foot x' , and vice versa. In the ends of the rods A' A^2 are elongated slots by which they fit over the studs y y' , whereby they are made to operate the feet x x' only on the extreme movements of the lever N —that is to say, when the lever is moving along the central portion of its stroke the rods A' A^2 slip along on the studs without engaging them, and only operate on them to move the feet x x' on the ends of the stroke. The reason for this is that if either of said feet were forced down to operate by the lever at its central position, the front feet, t , being also forced down by the lever in that position, would be in the way of the lever in the road-bed, and it could not move. And, again, the arrangement is such that the left-hand side foot x' is forced down

to operate at that extreme of the lever-stroke which forces down the right-hand rear foot r , which, being over to one side, does not interfere with the movement of the lever in the road-bed, and for the same reason the right-hand side foot x is forced down when the left-hand rear foot r' is projected. The side feet are in such position that when projected they are adapted to operate the lever F' , as do the other feet, and they are far enough over to operate it when the locomotive is on the siding. They are of such width as to straighten the lever F' , and throw the switch over to the main track from either siding. 70 75 80

Having thus described my invention, what I claim as new, and desire to secure by Letters Patent, is—

1. In a railway-switch, the combination of 85 the horizontal levers F F' , pivoted in the road-bed, the T -shaped levers H H' , pivoted in the road-bed and to the levers F F' , the lever I , pivoted in the road-bed and connected with the throw-rails of the track, said lever having 90 arms i , the rods J J' , connecting the arms of the levers H H' with the arms i , and suitable devices on the locomotive for moving said levers F F' , whereby power is transmitted through levers H H' , rods J J' , and lever I to 95 move the throw-rails into connection with the main or side tracks, substantially as herein described.

2. In a railway-switch, the combination of 100 the horizontal spear-like-shaped levers F F' , pivoted in the road-bed, the parallel side guide-bars, G G' , on each side of said levers, the pivoted T -shaped levers H H' , connected with levers F F' , the pivoted lever I , having arms 105 i , and connected with the throw-rails, the rods J J' , connecting levers H H' and lever I , and suitable projections or feet on the locomotive adapted to pass between either or both edges of the levers F F' , and the guide-bars G G' , whereby said levers are moved to transmit 110 power to move the throw-rails into connection with the main or side tracks, substantially as herein described.

3. In a railway-switch, the combination of 115 the horizontal levers F F' , having the series of holes a a' , by which they are pivoted and adjusted in the road-bed, the studs f , and the pivoted T -shaped levers H H' , having slotted legs, through which the studs f fit, and in which they are adapted to be moved or adjusted, substantially as and for the purpose 120 herein described.

4. In a railway-switch, the throw-rails C , having the tie-rod c , with a transverse rib, c' , and the series of spaced sockets b in the road-bed under the tie-rod, and into which the rib c' is adapted to fit, in combination with the pivoted horizontally-swinging lever I , and the connection between said lever and tie-rod whereby the throw-rails are moved sidewise, and 125 the rib of their tie-rod fitted in the different sockets, consisting of the upright arm c^2 on the tie-rod, having a notched top in which the end of lever I plays, the piece d , pivoted to the 130

upright arm, and through whose top the lever I passes, and the wheeled legs d' on the base of said pivoted piece, all arranged and operating substantially as and for the purpose herein described.

5. In a railway-switch, the horizontally swinging and adjustable levers F F' in the road-bed, connected with and adapted to operate by their movement the throw-rails, in combination with the pair of vertically-adjustable feet t under the locomotive, adapted to pass on each side of and impinge against the edges of levers F F' to move them to a straight position parallel with the tracks, whereby the switch-rails are thrown into connection with the main track, and a lever, N, and its connections for operating the feet, substantially as herein described.

6. In a railway-switch, the horizontally swinging and adjustable levers F F' in the road-bed, connected with and adapted to operate by their movement the throw-rails, in combination with the pair of narrow feet t and wider feet $r r'$ under the locomotive, and a lever and series of arms on said locomotive, adapted to alternately force downward said feet to engage with the levers F F', whereby they are forced to a straight or inclined position to either side to connect the throw-rails with the main track or either side track, substantially as herein described.

7. In a railway-switch, the adjustable spear-shaped levers F F', pivoted in the road-bed and connected by rods J J', and side guide-bars, G G', in combination with the vertically-adjustable oval or elliptical feet under the locomotive, adapted to enter and pass between said levers and bars to move the levers, substantially as and for the purpose herein described.

8. In a railway-switch in which the switch-rails are adapted to be moved by suitable levers in the road-bed, the feet $r r'$ on the locomotive, adapted to engage with and operate said levers to move the switch-rails to the side tracks, in combination with the mechanism for alternately projecting said feet to their engagement, consisting of the pivoted slotted arms Q Q', connected with the legs of the feet $r r'$, respectively, the crank-shaft U, having oppositely-extending cranks $u u'$, engaging with the slotted arms, the rock-shaft M, having crank-arm m , rod V, connecting said arm with the crank-shaft U and the lever N in the cab of the locomotive, substantially as herein described.

9. In a railway-switch in which the throw-rails are adapted to be moved by suitable levers in the road-bed, the combination of the pair of feet t on the locomotive adapted to engage with and operate the levers to move the throw-rails to the main track, and the mechanism for projecting said feet to their engagement and withdrawing them therefrom, consisting of the pivoted lever S, pivoted to the leg of the feet t , and having the curved slotted arm s, the shaft U, having crank u' engaging

with said slotted arm, the rock-shaft M, having crank-arm m , rod V, connecting said arm with crank u' , and the lever N, substantially as herein described.

10. In a railway-switch in which the throw-rails are adapted to be moved by suitable levers in the road-bed, the combination of the pair of feet t and the feet $r r'$ on the locomotive, adapted to engage with and operate said levers to move the switch-rails to the main track or to either side track, respectively, and the mechanism for alternately projecting or withdrawing said feet to or from their engagement, consisting of the pivoted lever S, connected with the leg of feet t , and having the slotted curved arm s, the pivoted slotted arms Q Q', connected, respectively, with the legs of feet $r r'$, the shaft U, having the oppositely-extending cranks u , engaging with the slotted arms Q Q', and the intervening crank, u' , engaging with the slotted arm s, the rock-shaft M, having crank-arm m , the rod V, connecting said arm with crank u' and the lever N in the cab, substantially as herein described.

11. In a railway-switch, the combination, with the lever F' in the road-bed, for operating the throw-rails, of the side feet, $x x'$, on the locomotive, adapted to engage said lever F' from a side track to throw the switch-rails to the main track, and mechanism, as described, for alternately projecting or withdrawing said feet to or from their engagement, substantially as herein specified.

12. In a railway-switch, the combination of the lever F' in the road-bed, by which the throw-rails are adapted to be operated, the side feet, $x x'$, on the locomotive, adapted to engage said lever F' from a side track to throw the switch-rails to the main track, and the mechanism for alternately projecting or withdrawing said feet from their engagement, consisting of the pivoted curved bars X X', to which said feet are joined, the pivoted links Y Y', and oppositely-inclined pivoted links Z Z', the rock-shaft M, having crank-arm m , connecting rods A' A'', joining said arm with the links Y Y', and the lever N in the cab, substantially as herein described.

13. In a railway-switch in which the throw-rails are adapted to be operated by a lever, F', in the road-bed, the combination of the alternately-adjustable feet $t r r'$ on the locomotive for engaging said lever from the main track, the side feet, $x x'$, on the locomotive, adapted to engage with said lever from a side track, in combination with the mechanism by which said feet $t r r' x x'$ are projected or withdrawn to or from their engagement to prevent interference one with the other, as described, consisting of the pivoted lever S, connected with the leg of feet t , and having the slotted arm s, the pivoted slotted arms Q Q', connected with the legs of feet $r r'$, respectively, the crank-shaft U, having cranks $u u'$ engaging with slotted arms s Q Q', the pivoted curved bars X X', to which the feet $x x'$ are

joined, the pivoted links Y Y', having studs
y y', the oppositely-inclined pivoted links Z
Z', the rock-shaft M, having crank-arm m , the
rod V, connecting said arm with crank u',
5 and the rods A' A'', connected with said arm,
and slotted on the studs y y' of links Y Y' and
the main lever N in the cab, all arranged and
operating substantially as and for the purpose
herein described.

In witness whereof I have hereunto set my 10
hand.

GEORGE CHALMERS.
